CIRCUIT BREAKER APPARATUS

Benjamin I. Hayford, Wilkinsburg, Pa., assignor to Westinghouse Electric & Manufacturing Company, East Pittsburgh, Pa., a corporation of Pennsylvania

Application March 29, 1934, Serial No. 717,975

8 Claims. (Cl. 254—3)

My invention relates, generally, to circuit breaker apparatus, and, more particularly, to apparatus for use in connection with circuit breakers which are enclosed within a cell structure and may be withdrawn from the cell for the purpose of inspection and repair, or for substitution of another circuit breaker.

It is the present practice to provide the cells which enclose the circuit breakers with self-contained elevating devices for raising the circuit breaker units into engagement with stationary contact members within the cells which are connected to the bus bars. This practice makes it unnecessary to mount each circuit breaker unit on an individual truck, thereby reducing the cost of the equipment in a switchgear station.

However, it is necessary to provide some means for transporting the breaker units within the station when it is desired to withdraw a circuit breaker from the cell structure for the purpose of inspection and repair or for substitution of another circuit breaker unit.

An object of my invention, generally stated, is to provide a transfer truck for circuit breaker units which shall be simple and efficient in operation, and which may be readily and economically manufactured.

A more specific object of my invention is to provide a transfer truck for circuit breaker units with a self-contained means for raising the breaker unit from the floor to permit it to be moved into or out of the cell structure and about the switchgear station.

Other objects of my invention will be explained fully hereinafter or will be apparent to those skilled in the art.

In accordance with the preferred embodiment of my invention, a transfer truck is equipped with lifting arms disposed to engage lugs provided on the sides of the circuit breaker unit. A simple elevating mechanism is provided for moving the lifting arms vertically a sufficient distance to raise the breaker unit from the floor, thereby permitting the breaker to be moved where desired without the use of hoists or cranes.

For a fuller understanding of the nature and objects of my invention, reference may be had to the following detailed description, taken in conjunction with the accompanying drawing, in which:

Figure 1 is a plan view of a transfer truck embodying my invention;

Fig. 2 is a view, in side elevation, of the transfer truck, showing a circuit breaker unit raised

from the floor by means of the elevating mechanism;

Fig. 3 is a view, in end elevation, of the transfer truck; and

Fig. 4 is an enlarged view, partly in section and partly in elevation, of a portion of the elevating mechanism.

Referring to the drawing, the transfer truck comprises a base frame, comprising two spaced longitudinal members 11, joined at one end by a cross member 12. A wheel or roller 13 is provided at the front end of each of the longitudinal members 11 and two swivel wheels 14 are provided at the rear end of the frame for supporting the truck. An upright member 15 is provided at each rear corner of the base frame and these upright members are joined at the top by a cross member 16. Likewise, an upright member 18 is provided at the front end of each of the base members 11. However, no cross members are provided at the front end of the frame, in order that it will straddle a circuit breaker housing to permit the breaker housing to be lifted from the floor in a manner hereinafter described.

As shown, a diagonal brace 19 is provided at each side of the truck frame. The braces 19 extend from near the bottom of the front uprights 18 to the top of the rear uprights 15 and may be secured thereto by welding or other suitable means. If desired, the ends of the braces 19 may be extended beyond the uprights 15 and joined by a pipe or rod 21, as shown, to constitute a handle for moving the truck.

In order that the transfer truck may be utilized to lift a circuit breaker unit 20 from the floor to transport the breaker unit, the truck is provided with a pair of spaced, horizontal arms 22 which are pivotally connected to the rear upright members 15 by means of a rod 23. The lifting arms 22 are joined at the rear by a channel member 24 and braces 25 are secured to the channel 24 and the arms 22, as shown in Fig. 1, to prevent lateral movement of the arms 22. In a similar manner, braces 26 are secured to the bottom longitudinal members 11 and the cross member 12 to prevent lateral movement of the front ends of the members 11.

As shown in Fig. 2, a toggle mechanism 31 is disposed to raise one end of each of the arms 22, thereby raising the breaker unit 20 which is provided with lugs 32 which are engaged by the arms 22. One link of each toggle mechanism is connected to one of the arms 22 and the other link is connected to one of the front upright members 18 by means of a bearing block 33 that may

be welded onto the upright 18. The two links are joined by a pin 34 to which one end of a rod 35 is connected for operating the toggle mechanism.

5 It will thus be seen that the ends of the arms 22 can be raised simultaneously to lift the breaker unit 20 by pulling both rods 35 toward the rear of the truck to actuate the toggle mechanism 31 to the position shown in solid lines. A stop member 36 is provided on each of the uprights 18 to prevent the toggle mechanisms from being actuated to, or past, the dead center position. A guide member 37 is also provided on the side of each of the lifting arms 22 to prevent lateral and longitudinal movement between the uprights 18 and the arms.

In order that the toggle mechanisms may be moved simultaneously from the position shown in broken lines to the position shown in solid lines, 20 thereby raising the breaker unit, by drawing the connecting rods 35 toward the rear of the truck, each of the rods is provided with a threaded connecting link or bolt 41 having a bifurcated head connected to the end of the rod 35, opposite the 25 toggle mechanism, by a pin 42. The threaded portion of each of the links 41 extends through a channel member 43 which extends across the rear of the truck frame and is secured to the upright members 15.

30 As shown, particularly in Fig. 4, a threaded sprocket wheel 44 is provided on the right hand one of the links 41, a thrust bearing 45 being interposed between the sprocket wheel and the channel 43. The thrust bearing 45 may be secured in position by screws 46. The sprocket 44 is provided with a collar 47 which surrounds the bolt 41 and has two projecting lugs 48 disposed to be engaged by a crank 49 having a slotted sleeve 51 for fitting over the collar 47 to rotate the sprocket 44.

40 A sprocket 52, which is similar to the sprocket 44 except that the collar 47 is omitted, is provided for the threaded link 41 on the connecting rod 35 that operates the toggle mechanism on the left hand side of the truck and the two sprockets are connected by a chain 53, as shown in Fig. 3, a thrust bearing similar to the bearing 45 is provided for the sprocket 52. A cover plate 54, which may be secured to the channel 43 by 50 screws 55 encloses and protects the two sprockets and the chain.

55 It will thus be seen that the two toggle mechanisms may be operated simultaneously either to raise or lower the arms 22 by turning the crank 56 49 in the proper direction. When the crank is turned in one direction the threaded links 41 are drawn through the sprockets which turn in the bearings 45, thereby operating the toggle mechanisms to raise the arms 22, and as the crank is 60 turned in the opposite direction the arms are permitted to drop, thereby raising or lowering the circuit breaker unit.

65 From the foregoing description, it will be apparent that I have provided a transfer truck which is simple in construction and operation and which may be readily utilized to lift heavy circuit breaker units from the floor and move them into or out of the cell structure, and about the switchgear station without the aid of a crane or hoist.

70 I do not desire to be restricted to the specific embodiment of my invention herein shown and described, since it is evident that it may be changed and modified without departing from the spirit and scope of my invention as defined in the 75 appended claims.

I claim as my invention:

1. A transfer truck for a circuit breaker unit comprising a truck frame, wheels for supporting the truck frame, a pair of spaced arms pivotally connected to the truck frame and disposed to straddle the circuit breaker unit and engage the sides thereof, separate toggle mechanisms for raising one end of each arm to lift the circuit breaker unit, and means for operating both toggle mechanisms simultaneously. 5

2. A transfer truck for a circuit breaker unit comprising a truck frame, wheels for supporting the truck frame, a pair of spaced arms pivotally connected to the truck frame and disposed to straddle the circuit breaker unit and engage the 15 sides thereof, separate toggle mechanisms for raising one end of each arm to lift the circuit breaker unit, and a common operating means for actuating both toggle mechanisms simultaneously to raise or lower the circuit breaker 20 unit. 10

3. A transfer truck comprising a truck frame, wheels for supporting the truck frame, a pair of spaced arms having one end pivotally connected to the truck frame, individual toggle mechanisms 25 disposed in substantially vertical alignment with the arms for raising the other end of said arms, means for actuating each of said toggle mechanisms, and common means for operating said actuating means simultaneously. 30

4. A transfer truck comprising a truck frame, wheels for supporting the frame, a pair of spaced arms having one end pivotally connected to the rear of the truck frame, individual toggle mechanisms disposed at the front of the truck frame 35 and in substantially vertical alignment with the arms for raising the front end of said arms, an operating mechanism disposed at the rear of the truck frame for actuating said toggle mechanisms, and means for connecting the actuating 40 mechanism to the toggle mechanisms.

5. A transfer truck comprising a truck frame, wheels for supporting the frame, a pair of spaced arms having one end pivotally connected to the rear of the truck frame, a toggle mechanism disposed at each side of the front of the truck frame and in substantially vertical alignment with the arms for raising the front end of said arms, an operating mechanism disposed at the rear of the truck frame for actuating said toggle mechanisms, and a connecting rod disposed on each side of the truck frame for connecting each of the toggle mechanisms to the operating mechanism. 50

6. A transfer truck comprising a truck frame, 55 wheels for supporting the frame, a pair of spaced arms having one end pivotally connected to the rear of the truck frame, a toggle mechanism disposed at each side of the front of the truck frame for raising the front end of said arms, a connecting rod disposed on each side of the truck frame, one end of each rod being connected to one of said toggle mechanisms, and operating means disposed at the rear of the truck frame for moving said connecting rods longitudinally 60 to actuate the toggle mechanisms. 65

7. A transfer truck comprising a truck frame, wheels for supporting the frame, a pair of spaced arms having one end pivotally connected to the rear of the truck frame, a toggle mechanism disposed at each side of the front of the truck frame for raising the front end of said arms, a connecting rod disposed on each side of the truck frame, one end of each rod being connected to one of said toggle mechanisms and the 75

other end of each rod being provided with a threaded connection, and threaded means disposed at the rear of the truck frame to cooperate with the threaded connections on said rods to move the rods longitudinally to actuate the toggle mechanisms.

8. A transfer truck comprising a truck frame, wheels for supporting the frame, a pair of spaced arms having one end pivotally connected to the rear of the truck frame, a toggle mechanism disposed at each side of the front of the truck frame for raising the front end of said arms, a

connecting rod disposed on each side of the truck frame, one end of each rod being connected to one of said toggle mechanisms and the other end of each rod being provided with a threaded connection, threaded sprocket wheels disposed at the rear of the truck frame to cooperate with the threaded connections on said rods to move the rods longitudinally to actuate the toggle mechanisms, means for connecting the sprocket wheels, and means for rotating said sprocket wheels. 5 10

BENJAMIN I. HAYFORD.
